INVENTOR
JOHN HOHL

BY
R. J. Hohm ATTORNEY

UNITED STATES PATENT OFFICE.

JOHN HOHL, OF NEWARK, NEW JERSEY.

ELECTRIC SOCKET.

Application filed March 27, 1923. Serial No. 627,947.

To all whom it may concern:

Be it known that I, JOHN HOHL, a citizen of the United States of America, residing at Newark, county of Essex, State of New Jersey, have invented a new and useful Electric Socket, of which the following is a specification.

My invention relates particularly to what are sometimes termed separable sockets, and 10 particularly for electric lamps. In such constructions there is usually a cap which serves as a mounting for a lamp cord or as a means of attachment to a fixture and a body portion for containing a switch or 15 accommodating a lamp base.

The main object of my invention is to so construct the parts of such a device that they may be readily connected and readily separated, when intended, but in which the 20 parts are clearly so connected that they cannot be accidentally or unintentionally separated.

In the preferred embodiment of my invention, I have sought to connect the parts 25 in such a way that they are automatically locked together when a lamp base or the like is inserted and so that the parts of the socket can not be separated when the lamp base or other current consuming device is 30 inserted.

In the simple preferred form herein illustrated, I have provided interlocking parts and a latch bolt which is automatically actuated by the lamp base, current tap or 35 similar base.

Fig. 1 is a longitudinal sectional view of a construction embodying the improvements 40 of my invention, showing a lamp base in position and parts of the socket locked together, the socket being shown on the plane of the line 1—1 of Fig. 2.

Fig. 2 is a plan view of the switch-carrying portion of the socket.

Fig. 3 is an interior end view of the cap 45 of the socket detached.

Fig. 4 is a longitudinal sectional view of the body of the socket and attached parts on the plane of the line 4—4 of Fig. 2.

Fig. 5 is a detailed perspective view of the 50 latch bolt.

The shell or casing of the socket may be formed of any suitable material, for instance, molded insulation, and has a cap portion 6 and a body portion 7, which prefer- 55 ably have interfitting flanges. The cap is provided with circuit terminal members 8

and 9 suitably secured in place, these terminal members are provided with circumferentially extending offset fingers 10 and 11 adapted to engage corresponding offset portions of the brackets 12 and 13, which are carried by the portion 7 of the socket. These brackets 12 and 13 may be secured suitably in the body, as, for instance, by one or more screws 14 and 15. The parts are adapted to 60 be connected by a longitudinal movement of the body of the socket with respect to the cap and a relative rotational movement of approximately ninety degrees (90°), the fingers 10 and 11 and brackets 12 and 13 65 being designed to permit of this limited relative movement.

In the construction shown, I have provided a switch having two spring contacts 16 and 17 mounted in the body of the socket. 75 The contact 16 is clamped to the body by the foot of the bracket 12 and the contact 17 is secured in place by means of the foot of the yoke 18 and the screw 19. The yoke 18 also affords a support for the key spindle 80 20, which carries the loose contact maker or cam 21.

I have shown the invention as applied to a screw shell type of socket having the center contact 22 secured by the screw 19 and 85 having the screw shell 23, which may be either molded in place or secured by means of one of the screws 15. The screw base 24 may be considered as typifying either a lamp base, a current tap or other screw base 90 for some form of current consuming or conducting device.

The latch member is in the form of a bolt 25 carried by the body of the socket and 95 having an operating spring 26, which tends to resiliently hold the bolt in the position shown in Fig. 4, in which the head 27 projects alongside the screw shell 23 in the path of movement of the screw base 24. The finger 11 which is carried by the cap has a 100 passage 28, which is in line with the passage 31 in the bracket 13, when the parts are in their assembled position. It will be obvious that when the bolt 25 is inserted through the openings 28 and 31, the brackets 105 13 and members 11 will be prevented from relative rotational movement and thus the cap and body of the socket will be held positively against separation. When the screw base 24 is inserted in the socket it automatically engages the head 27 of the latching bolt 25 and forces the opposite end 110

through the holes 28 and 31 and securely locks the parts together. Contrariwise when the screw base 24 is removed from the socket, the latch bolt 25 is automatically retracted and the parts of the socket may be readily separated by simply rotating the body with respect to the cap, and then pulling the body and cap apart.

As additional security for holding the parts of the socket yieldingly together when the latch bolt 25 is retracted, I may provide the brackets 12 and 13 with small bosses, such as 29 and provide the fingers 10 and 11 with recesses 30 adapted to receive them when the parts are in their interlocked relation, it being understood that the parts have sufficient resiliency to permit the engagement and disengagement of these projections and recesses.

20 I claim:

1. An electric socket comprising a body adapted to receive a lamp base, a cap, means for detachably securing the cap to the body, and means responsive to the insertion of a lamp base in the body for locking the cap and body against separation.

2. An electric socket comprising a body adapted to receive a base, a cap for the body, members on the cap and body arranged to be rotated into interlocking engagement, and means operated by the insertion of a base in the body to prevent disengagement of said members.

3. An electric socket comprising a body adapted to receive a base, a cap, for the body, members on the cap and body arranged to be interlocked upon rotation of the cap relative to the body in one direction, and means operated by the insertion of a base in the body to prevent disengagement of said members.

4. In combination, a body adapted to receive a lamp base, a cap for the body, engaging members to detachably secure the cap to the body, and a bolt moved by insertion of a lamp base into the body to lock said engaging members.

5. An electric socket comprising a body adapted to receive a lamp base, a cap, means for detachably securing the cap to the body including interlocking fingers, and means responsive to the insertion of a lamp base in the body for locking the cap and body against separation including a bolt engaging said fingers.

6. An electric socket comprising a body adapted to receive a base, a cap for the body, members on the cap and body arranged to be rotated into interlocking engagement, and spring pressed means operating while a base is in the body for preventing disengagement of said members.

7. An electric socket comprising a body adapted to receive a base, a cap for the body, members on the cap and body arranged to be interlocked upon rotation of the cap relative to the body in one direction, and means operating while a base is in the body for preventing disengagement of said members and automatically retractable when the base is withdrawn.

8. A lamp socket construction comprising a body part having a recess for receiving a lamp base, a cap part having circuit terminals, hooks carried by said parts and connectible by relative rotary movement of said parts and a latch bolt for preventing relative rotation of said parts, said bolt having an operating portion projecting into said recess.

9. In combination, a body adapted to receive a lamp base, a cap for the body, engaging members to detachably secure the cap to the body, and a bolt moved by a lamp base in the body to lock said engaging members.

10. An electric socket comprising a body adapted to receive a lamp base, a cap, means for detachably securing the cap to the body, and means for locking the cap and body against separation including a spring pressed controlling member projecting into the socket opening in the path of the lamp base adapted to be operated by the insertion of a lamp base and adapted to be automatically released when the lamp base is removed.

11. A lamp socket comprising a body part having a recess for receiving a lamp base, a cap part having circuit terminals, two pairs of interlocking conductors carried by said parts and adapted to be connected together by relative longitudinal and rotative movements of the cap and body and a spring pressed latch bolt engaging one pair of said interlocking conductors to prevent relative rotation of said parts said latch bolt having an operating part projecting into said recess and adapted to be engaged and operated by a lamp base inserted in said recess.

JOHN HOHL.
